UNITED STATES PATENT OFFICE.

ALONZO G. DECKER, OF TOWSON, MARYLAND, ASSIGNOR TO THE BLACK AND DECKER MANUFACTURING COMPANY, OF TOWSON, MARYLAND, A CORPORATION OF MARYLAND.

DESIGN FOR A CASING FOR PORTABLE POWER-DRIVEN TOOL.

Application filed January 7, 1928. Serial No. 24,769. Term of patent 14 years.

To all whom it may concern:

Be it known that I, ALONZO G. DECKER, a citizen of the United States of America, residing at Towson, Baltimore County, Maryland, have invented a new, original, and ornamental Design for Casing for Portable Power-Driven Tool, of which the following is a specification, reference being had to the accompanying drawing, forming part thereof.

Figure 1 is a top plan view of the tool casing showing my new design.

Figure 2 is an elevation looking at the casing from the side remote from the observer in Figure 1.

I claim—

The ornamental design for a casing for portable power driven tool substantially as shown.

Signed by me at Towson, Maryland, this 28th day of December, 1927.

ALONZO G. DECKER.
